ATTORNEY.

UNITED STATES PATENT OFFICE.

ALLEN ALFORD, OF WACO, TEXAS.

ROCK-DRILL.

1,387,447.

Specification of Letters Patent. Patented Aug. 16, 1921.

Application filed July 28, 1920. Serial No. 399,483.

To all whom it may concern:

Be it known that I, ALLEN ALFORD, a citizen of the United States, residing at Waco, in the county of McLennan and State of Texas, have invented certain new and useful Improvements in Rock-Drills, of which the following is a specification.

This invention relates to improvements in well drilling tools and it relates more particularly to a rock drill and to the arrangement and construction of such a drill.

The principal object of the invention is to provide an improved drill for quickly boring or cutting through hard formations such as rock, sandstone and the like, the drill being provided with cutting surfaces for cutting or boring through these formations according to their degree of hardness. Other improved features such as the ready removal of the drill parts and means for affixing these parts in the drill body will be referred to in the following description and accompanying drawings wherein—

Figure 1 is a side elevational view of a drill body illustrating my invention.

Fig. 2 is a vertical sectional view.

Fig. 3 is a cross sectional view taken on line 3—3 of Fig. 1.

Fig. 4 is a top view of the end or drill bit removed from the body, and

Fig. 5 is a fragmentary detail sectional view of a modified arrangement of the blades in the drill body.

Referring more particularly to the drawings, 1 denotes the drill body which is of frusto-conical formation and centrally bored for the water line 2 and provided with a screw-threaded recess indicated at 3 for the reception of a drill bit 4 which is also centrally bored to provide a continuation of the water line 2. The water line 2 extends to within a short distance of the end of the bit 4 where it is reduced in diameter into the radials 5—5 and a lower outlet 6. The drill bit 4 as will be noted by reference to Figs. 1 and 4 is cone-shaped and has its outer surface corrugated or roughed in the form of the ridges or ribs 7—7 to bite into the sandstone or other stratum. As the outer surface wears away the nose or point 8 is kept continually sharpened by reason of the fact that when the outer or ribbed surface of the bit is worn inward the wall of the outlet 6 will form a sharp edge or point with the outer surface or ribs 7—7.

Slots traversing the body 1 from side to

side are provided for receiving the blades 9—9. These blades as will be noted by reference to Figs. 1 and 2 project through the body at right angles to each other. The ends 60 of the blades have an angular parallel relationship to the body 1, each blade being increased in length from the bottom to the top of the body, so that its projecting ends will extend outward from the body the same distance in an upwardly increasing ratio. The blades are locked in position by set screws 10—10. The lowermost blade when in position locks the drill bit 4 in the body as this blade, see Fig. 2, rests in the slots 11—11, 70 see also Fig. 4.

The drill bit 4 will bore into the hard strata and as the hole is deepened the lowermost of the blades 9—9 will take hold to increase the diameter of the hole and so on upward until the topmost blade is reached where the full diameter is attained. On account of the conical formation of the drill body and its blades a hole in hard formation can be more quickly bored as is obvious than 80 if the blades and body were on vertical parallel lines.

Where the formation in the well is very hard I have provided a modified form of blade, illustrated in Fig. 5. In this form the 85 shoulder of the blade is flush with the surface of the body 1 and has a small protuberance 12 with its end on an angle with the body. A roller 13 with a corrugated or ribbed outer face 14 and edges 15 is rotatably 90 mounted upon the protuberance 12 and held to position by a screw or axis 16. This form of blade with rollers is held in the body 1 by set screws similar to the blades shown in Fig. 2, it being only necessary to remove the 95 set screws 10 and the rollers 13 when inserting the style of blade shown in Fig. 2.

Having thus described the nature and objects of my invention, what I claim is—

1. A well drilling tool for hard formations such as rock, sandstone and the like, comprising a frusto-conical drill body, a conical drill bit detachably secured to one end thereof, a plurality of blades traversing the drill body from side to side through the body, means for locking the drill bit in position in the body to one of the blades, and channels for a water line in the body and bit.

2. A drilling tool for wells for boring rock and similar hard formations, comprising a conoidal shaped drill body and a conical bit on one end thereof, a plurality of supporting

members placed through the drill body from side to side and extending from the top to the bottom of the body from opposite sides of the body and extended beyond the periphery of the body, corrugatedly surfaced rotatable rollers on the ends of the supporting members, means for securing the supporting

members in the body and for locking the drill bit in the body and onto the lowermost supporting member.

10

In testimony whereof I have signed my name to this specification.

ALLEN ALFORD.
